UNITED STATES PATENT OFFICE.

ARTHUR E. TRUESDELL, OF PITTSFIELD, MASSACHUSETTS.

KILN.

No. 828,985.

Specification of Letters Patent.

Patented Aug. 21, 1906.

Application filed December 5, 1904. Serial No. 235,438.

To all whom it may concern:

Be it known that I, ARTHUR E. TRUESDELL, a citizen of the United States, residing at Pittsfield, in the county of Berkshire and 5 State of Massachusetts, have invented an Improvement in Kilns, of which the following description, in connection with the accompanying drawings, is a specification, like characters on the drawings representing like 10 parts.

This invention relates to that type of kiln wherein a moderate burning temperature is essential; and its object is to provide means whereby the temperature of the products of 15 combustion and the volume and duration of the flame may be controlled or regulated, according to the character of the fuel used for generating the heat.

In the burning of lime, for which my present invention is particularly well adapted, it is essential that the heat generated for a material length of time shall not exceed 1,000° centigrade, for if a greater temperature than this is produced the silicates and other fusible impurities present in the lime-rock will fuse and form a slag on the outside of the rock, which prevents the proper burning and results in an inferior product. Furthermore, it is essential to commercial operation that 25 this heat should be distributed through a comparatively large body of material, or, in other words, that the flame caused by the combustion of fuel should be one of large volume. Accordingly it has been customary 30 heretofore to use wood as the fuel, for while wood has a comparatively low calorific power, yet it yields sufficient heat to effect the calcination of the lime-rock, and the flame therefrom is of sufficient volume to result in evenly 35 burning the lime. It is sometimes impracticable or impossible to obtain sufficient wood for the purpose, owing to the increasing scarcity and high price of this fuel. Fuel such as coal, coke, oil, or gas as ordinarily burned 40 in air during the process of combustion generates an intense local heat, but does not generate a sufficient volume of flame to properly burn the lime. The result is that where 45 these fuels are used in burning lime the portion of the lime-rock adjacent to the fuel during its combustion is overburned, while portions of lime-rock at some distance do not receive sufficient heat to become properly 50 burned. Furthermore, the intense heat generated by burning these fuels causes the rapid 55

deterioration of the fire-brick linings of the combustion-chambers.

It is the object of my present invention to provide a novel form of kiln in which fuel—such as coal, coke, &c., may be advantageously used, and I accomplish this by providing means whereby the available heat units are liberated and used at the temperature most suitable to the material being calcined or fired without producing such extremes of temperature in the burning portions of the kiln as to cause the over or under burning of the product.

In applying my invention to a kiln of the "ring-and-oven" type I place between each 70 two adjacent kiln-chambers one or more furnaces or "generating-chambers," which are so constructed that they act as gas-producers—that is, producer-gas is generated in them, and the gas after being generated in 75 any one is delivered to the succeeding kiln-chamber or kiln-chambers. When this gas enters the kiln-chambers in which the material is to be burned, it is commingled with air which is delivered to said chambers in order 80 that combustion may take place, the amount of air being so delivered and regulated, according to the character and amount of gas delivered, that a flame of the requisite temperature will be formed to properly burn the 85 material in the kiln-chamber. By controlling the amount of air and the points where it is delivered to and commingled with the producer-gas the burning-flame may be stretched out, as it were, not only through 90 the next succeeding kiln-chamber, but through two or three succeeding kiln-chambers, if necessary, to produce the flame of the right temperature and volume. The temperature of the flame may be further regulated and modified by introducing steam into 95 the gases prior to their combustion in the kiln-chamber. This introduction of steam may or may not be suitable with all classes of product, but with lime it is an advantage, because it not only modifies the temperature of the flame, but assists in the liberation of CO₂ from the stone, which latter operation takes place at a lower temperature when steam is present in the gas. The heat units in the 100 fuel may therefore be liberated at the temperature most suitable for burning the material being fired and at widely-distributed points, so that an even burning may be effected with little or no deterioration of the 105 110

brick linings of the kiln. The generating chambers or furnaces are arranged in series with the kiln-chambers, so that the current passing through the successive chambers can 5 be taken from one kiln-chamber to the next kiln-chamber through the intermediate generating chamber or chambers.

I prefer to employ downdraft generating-chambers—that is, generating-chambers in 10 which the draft through the fuel therein is downwardly instead of upwardly—and for this purpose each generating-chamber has an inlet port or duct at its upper end connecting with the upper end of the preceding kiln-chamber and a discharge port or duct at its 15 lower end communicating with the succeeding kiln-chamber.

In the drawings, which show one form of my invention, Figure 1 is a top or plan view 20 of a kiln embodying my invention. Fig. 2 is a transverse vertical section through the kiln shown in Fig. 1. Fig. 3 is a top plan view of a portion of the kiln on the same scale as Fig. 2, said view showing the kiln-chambers and 25 generating-chambers open and the covers removed from the chambers 20. Fig. 4 is a section, on an enlarged scale, on the line *y* *y*, Fig. 3. Fig. 5 is a section, on an enlarged scale, on the line *a* *a*, Fig. 3. Fig. 6 is a 30 detail hereinafter described. Fig. 7 is a section on an enlarged scale, on the line *c* *c*, Fig. 1. Fig. 8 is a horizontal section through Fig. 7. Fig. 9 is a detail of the portable forced-draft apparatus. Fig. 10 is an end view of Fig. 9. 35 The kiln shown in the drawings is of the ring-and-oven type, and therefore the kiln-chambers are arranged in series and are connected together consecutively.

I have illustrated herein twenty kiln-chambers, and they are designated by *a'*, *a²*, *a³*, *a⁴*, 40 *a⁵*, *a⁶*, to *a²⁰* and are arranged in two rows or series. Between the two rows of kiln-chambers is a smoke-flue 300, to which all or a part of the kiln-chambers may be connected and 45 into which the products of combustion are delivered. Suitable draft in the smoke-flue 300 may be induced in any suitable way, either mechanically, as by a fan or steam-jet, or by means of a chimney 30^a. I prefer to use both 50 a chimney and a steam-jet, as will be more fully explained hereinafter. Situated between each two adjacent kiln-chambers are one or more (two in this embodiment of my invention) furnaces for generating gas, which 55 furnaces I will hereinafter refer to as "generating-chambers." The generating-chambers corresponding to the kiln-chamber *a'* are designated by *b'*, those corresponding to the kiln-chamber *a²* are designated *b²*, those corresponding to the kiln-chamber *a³* are designated *b³*, &c. The particular construction 60 of the generating-chambers will be herein-after described more at length.

I have illustrated the kiln as provided with 65 a tunnel 3 beneath each row of kiln-chambers,

and each kiln-chamber has an upper charging-opening through which said kiln-chamber may be charged with unburned material, and a lower discharging-opening, through which the burned material can be discharged into a 70 car 5 on a track 4 in one of the tunnels. The charging-opening is at the top of each kiln chamber and is adapted to be closed by a suitable cover 12, and the discharging-opening is herein illustrated as in the bottom of 75 each chamber and as closed by one or more bricks or blocks 6, which are supported on wedge-shaped strut members 7, the latter resting on a plate 8, which is detachably clamped to the flange 9 of a collar 10, surrounding the discharging-opening. The closures for the charging and discharging openings are so constructed that when in place 80 said openings are closed to the passage of air. Above the kiln-chambers I propose to place 85 an elevated trackway 13, on which a carrier 14 may run for the purpose of conveying the material to the kiln-chamber which is to be fired. With this construction of kiln-chamber the operation of charging and discharging 90 is greatly facilitated by the action of gravity.

The generating-chambers are each provided with grate-bars 15, on which the fuel rests, and an open top, through which the fuel is delivered to the chamber. As stated above, 95 these generators are of the downdraft type—that is, the draft passes downwardly through them during the process of burning the fuel rather than upwardly through them. For this purpose each generating-chamber has 100 near its top an inlet or draft port 21, which leads into a duct or passage 20, communicating with the top of the preceding kiln-chamber, and at its bottom a discharge-port 24, which leads into the following kiln-chamber. 105 I prefer to arrange the mouth or delivery end of the discharge-passage 24 near the cooler part of the kiln-chamber, and for this purpose provide each chamber with the false bottom 26, which forms the top of a portion 110 of said discharge-duct 24, as best seen in Fig. 5. Between each pair of generating-chambers is a vertically-extending by-pass duct 27, which communicates at its upper end with the preceding kiln-chamber through a duct 115 or port 28 and at its lower end with the following kiln-chamber through a port or duct 29. (See Fig. 4.) Each of the by-pass ducts 27 is provided with a suitable valve by which it may be closed, which in this form of my invention is merely a brick or block 30, which can be slid over the upper end of the duct 27. The inlet-ports 21 for each generating-chamber are controlled by suitable valves, preferably in the form of blocks 23, which can be 120 moved to cover or uncover said ports, as desired. Each of the chambers 20 is provided with a suitable removable cover 31, and either all or a portion of the kiln-chambers are connected with the smoke-flue 300 by means of 125 130

short flues 39, which may be opened or closed by the valves 32, as seen in Figs. 7 and 8. Each chamber 20 is large enough to accommodate a portable device for creating forced draft in the generating-chamber, the device herein shown being a jet-blower or steam-jet apparatus such as is shown in Fig. 9, which consists of a sleeve or hollow member 60, the bore of which is choked slightly, as at 61, and 5 a steam-jet pipe 62 to deliver steam into the open end of said sleeve. I propose to use two of these steam-jet apparatus, one in chamber 20 at each side of any given kiln-chamber, and said apparatus will preferably be made 10 portable, so that they can be advanced from one chamber to another as the fire advances around the kiln. Each steam-jet pipe 62 is capable of being detachably secured to a steam-pipe 63, connected to any suitable 15 boiler. (Not shown.)

The operation of the kiln as thus far described is as follows: Assuming that the kiln-chamber a^4 is about to be fired, that the kiln-chamber a^3 has just been fired, that the kiln-chamber a^{17} has just been discharged and is 20 open for recharging, and that the kiln-chamber a^{18} is being discharged, the valve 32 is opened to connect one of the chambers 20, corresponding to the kiln-chamber a^{16} , with 25 the smoke-flue 300, and the valves 23 of both said chambers 20 are placed so as to close the inlet-ports 21, leading to the generating-chambers b^{17} , and a steam-jet is placed in 30 each of the two chambers 20, corresponding to the kiln-chamber a^3 . With this arrangement the draft induced by the chimney and steam-jet draws fresh air into the kiln-chamber a^{18} , from which it passes through the generating-chambers b^{19} into the kiln-chamber 35 a^{19} , and thence through the generating-chambers b^{20} and kiln-chamber a^{20} into a cross-duct 35, which connects the kiln-chamber a^{20} with the generating-chambers b' . Said current of air then passes on through the various 40 kiln and generating chambers until the kiln-chamber a^3 is reached. The burning of the material in the kiln-chamber a^4 is effected by the gas produced in the generating-chambers b^4 , and therefore, going on the assumption 45 above made, it will be understood that said generating-chambers b^4 are filled with coke or similar fuel which is being gasified. When the current of air reaches kiln-chamber a^3 , it becomes divided, one portion being forced by 50 the steam-jets through the generating-chambers b^4 and the other portion passing directly from the kiln-chamber a^3 to the kiln-chamber a^4 through the by-pass 27. The air which is 55 forced through the generating-chambers b^4 becomes converted into producer-gas as it passes through the fuel-bed in the said generating-chambers, and this gas is delivered to the kiln-chamber a^4 through the discharge-ducts 24. The amount of gas thus produced 60 depends upon the amount of air which is

forced through the generating-chambers, and this can be regulated by manipulating the valves 23. The producer-gas is delivered to the kiln-chamber a^4 at two points, both beneath the unburned material therein, and as 70 it passes upwardly through and distributes itself throughout the unburned material in said chamber it becomes commingled with the air which is delivered to said kiln-chamber through the by-pass duct 27, and combustion takes place. The burning of the material is effected partially by the heat of the incandescent fuel in the generating-chambers, which heat is transmitted through the partition between said chambers and the 75 kiln-chamber and partly by the combustion of the producer-gas, which combustion takes place when said gas becomes commingled with the air delivered through the by-pass duct 27. From the kiln-chamber a^4 the gases pass 80 through chambers b^5 a^5 b^6 a^6 , &c., and finally emerge from the kiln-chamber a^{16} through the duct 39 into the smoke-flue 30, said gases on their passage through kiln-chambers a^5 a^6 85 a^7 , &c., giving up their heat to the unburned material therein.

By means of the construction of kiln above described and the character of gas used it is possible to get the desirable even temperature in the kiln-chamber a^4 , for it will be 90 noted that the gas, which is hotter than the air, is introduced into the kiln-chamber at the point naturally the coolest, being farthest from the generator, and the air which is at a lower temperature than the gas is introduced 95 at the rearmost place, close to the generator. Both the air and gas are introduced into the kiln-chamber beneath the unburned material therein, and as they rise through said material they become gradually mixed, and 100 combustion is thereby made gradual and is evenly distributed.

I find it of advantage in the operation of the kiln to introduce more steam into the "primary" air, or that which is drawn 105 through the generating-chamber, than is supplied by the steam-jets, as such added quantity of steam not only gives a lower temperature in the generating-chamber, but also enriches the gas produced therein by forming a 110 mixture of water-gas and producer-gas. This excess steam may be provided in a variety of ways, either by taking the steam from a central steam-generating plant and introducing 115 it into the proper generating-chambers or by 120 providing portable steam-generators which can be used at each generating-chamber or in any other suitable way. In the form of the invention herein shown I use a portable steam-generator, which comprises a steam-generating pan 65, attached to the cover 66 of the generating-chamber by a pipe 67, through which the pan is supplied with water as needed. (See Fig. 6.) These steam-generating covers can be shifted from one gen- 125 130

erating-chamber to another, and thus used in conjunction with that generating-chamber in which the fuel is being burned.

In my present invention I provide means for introducing steam into the gas-discharge duct 24 of each generating-chamber. While this may be accomplished in several ways, I find a convenient way to be to provide a steam-pipe 46 in each of the tunnels 3, which steam-pipes are each provided with nipples 47 opposite each pair of generating-chambers. A distributing-pipe 48 can be attached to any nipple 47 for carrying steam from the supply-pipe 46 into the ducts 24. Said distributing-pipe is provided with nipples 49, which connect with pipes 500, extending into the space beneath the grates 15. The amount of steam thus delivered through the distributing-pipe 48 will depend somewhat on the character of the rock being burned and on the temperature which is desired and other attendant circumstances.

The combustion in the kiln-chamber may be modified or controlled by the valve 30, which controls the admission of air to said chamber, and the valve which controls the admission of steam into the gas. Excess of air shortens the flame and localizes the heat, while deficiency of air stretches out the flame, even to the extent of more than one kiln-chamber, and thus distributes the heat. The admission of steam into the gas lowers the temperature of the flame. Hence by means of the construction above described the temperature is not only controlled, but the chamber is evenly heated in all parts.

Whenever during the operation of the kiln it is observed that the material in any kiln-chamber is completely burned, it becomes necessary to start a fresh fire in the generating-chambers for the succeeding kiln-chamber, at which time, if desirable, the valve 32 may be closed, and the next in circuit may be opened to include fresh chambers in the circuit. At this time the generating-chambers abandoned may be isolated from the air-current by closing the valves 23 and their contents discharged at any later time, or their contents may be immediately discharged and while hot screened and used in starting the generators which are next to be fired. In any case the valve 30 is opened wide to afford free circulation of air to the following generator.

To facilitate the operation of drawing the fire while the coal is still hot, I have so constructed my generating-chambers that the contents thereof may be discharged through an opening in the bottom either onto the ground or into a car. For this purpose I so construct each generating-chamber that the grate-bars 15 rest at one end upon a shoulder 17 and at the other end on a supporting-strut or brick 18, which in turn rests on a plate 16, supported by wedge-shaped blocks 51.

These wedge-shaped blocks are situated in the throat or discharge-opening and rest on plates 19, which are detachably clamped to an outturned flange on the collar 50, surrounding the discharge-opening. With this construction the drawing of the fire involves merely the removal of the clamps which hold the plate 19 to the flange, for as soon as said clamps are removed the supporting-blocks 51, strut 18, grate-bars 15, and material in the generating-chamber all drop through the discharge-opening by the action of gravity. After the fuel has been discharged the joint between the plate 19 and the collar 50 is sealed, so as to prevent air being drawn in at this point.

In practice I propose to extend each pipe-section 500 through one of the wedge-shaped supporting-struts 51 and to make such pipe-section rigid with said strut. 85

On firing the next pair of generating-chambers the two steam-jet apparatus are removed from the ducts 20 in which they are located and placed in ducts 20 leading into the generating-chambers to be fired, and after these generating-chambers are fed with fuel the steam-jets are started, which results in the production of gas and combustion of same, as above described. Meanwhile chambers of material are being emptied and filled in the rear, and so the operation of the kiln is continuous.

Some of the advantages of the downdraft type of generating-chambers over the up-draft type are, first, that the top of the kiln 100 remains cooler, and consequently radiation from the kiln is less; second, the covers are cooler, and hence less liable to be broken; third, the handling of the kiln is less arduous; fourth, the gas is better distributed in 105 the kiln-chamber; fifth, it is much easier to observe the process of burning, and, sixth, better control of the temperature in the generating-chambers is secured.

Some of the advantages of a kiln in which 110 the generating-chambers alternate with the kiln-chambers instead of a kiln having a single outside generator from which the gas is distributed to the various kiln-chambers are, first, the saving of the heat units lost in radiation from the single generator and piping therefrom; second, the introduction of gas and air into the kiln-chamber to give an even heat is facilitated; third, deposit of soot in the pipes is avoided, and, fourth, the air for 115 the generator is preheated, and energy to that extent is utilized.

Although the construction herein illustrated is that which I deem to be preferable, yet the details of the kiln may be varied in 125 many ways without departing from the invention.

The kiln herein shown is of the ring-and-oven type; but my invention is not limited to this type of kiln, for with appropriate modi- 130

fications many of the features of the invention could be embodied in kilns of the ring type and in other forms of kilns.

Having fully described my invention, what I claim as new, and desire to secure by Letters Patent, is—

1. In a ring-and-oven kiln, a plurality of kiln-chambers, and a similar number of gas-generating furnaces, each furnace having its outlet-flue or discharge - port connected to one kiln-chamber, and its inlet or draft port connected to another kiln-chamber.
2. In a kiln, a plurality of kiln-chambers and a corresponding number of downdraft gas-generating furnaces, each furnace being connected with the corresponding kiln-chamber.
3. In a kiln, a plurality of kiln-chambers, and a downdraft gas-generating furnace for each kiln-chamber, each furnace having a gas-outlet port opening into the bottom of the corresponding kiln-chamber beneath the material therein.
4. In a kiln, a plurality of kiln-chambers, and a gas-generating furnace for each kiln-chamber, each furnace having an outlet-port to deliver gas to the bottom of the corresponding kiln - chamber beneath the material therein.
5. In a kiln, a plurality of kiln-chambers, separate means adjacent each kiln-chamber to generate gas and deliver it to said chamber beneath the material therein.
6. In a kiln, a plurality of kiln-chambers, and means adjacent each kiln-chamber to generate gas and deliver it to the bottom of said chamber beneath the material therein.
7. In a kiln, a plurality of kiln-chambers, and a downdraft gas-generating furnace for each kiln-chamber, each furnace having an outlet-duct communicating with the bottom of the corresponding kiln-chamber beneath the material therein.
8. In a kiln, a kiln-chamber, a downdraft-furnace having an outlet-duct communicating with the bottom of said chamber beneath the material therein, and means to admit steam to the top of the furnace, whereby water-gas is generated.
9. In a kiln, a kiln-chamber, a downdraft-furnace having an outlet-duct communicating with the bottom of said chamber beneath the material therein, said furnace being constructed to generate producer-gas, and means to admit steam to the top of the furnace, whereby combined producer-gas and water-gas is generated.
10. In a kiln, a plurality of kiln-chambers, a furnace situated between each two adjacent kiln-chambers and arranged to deliver gas to one of said kiln - chambers and having a valved passage connecting with the other kiln - chamber, said furnace being separate from the kiln-chambers.
11. In a kiln, a plurality of kiln-chambers,

a downdraft-furnace between each two adjacent kiln-chambers, a valved inlet-port connecting the top of each furnace with the preceding kiln-chamber, and an outlet-port connecting the bottom of each furnace with the succeeding kiln-chamber.

12. In a kiln, a series of kiln-chambers, a furnace between each two adjacent kiln-chambers, each furnace being connected to the chambers on either side thereof, and a by - pass duct directly connecting adjacent kiln-chambers.

13. In a kiln, a series of kiln-chambers, a downdraft-furnace between each two adjacent kiln-chambers, each furnace having an inlet-duct at its top communicating with the preceding kiln-chamber and an outlet-duct at its bottom connecting with the succeeding kiln-chamber, and a by - pass duct directly connecting adjacent kiln-chambers.

14. In a kiln, a series of kiln-chambers, a downdraft-furnace between each two adjacent kiln-chambers, each furnace having a valved inlet-duct at its top communicating with the preceding kiln-chamber, and an outlet-duct at its bottom connecting with the succeeding kiln-chamber, and a valved by-pass duct directly connecting adjacent kiln-chambers.

15. In a kiln, a plurality of kiln-chambers, a furnace for each kiln-chamber, said furnace being constructed to generate a mixture of producer and water gas, and means to commingle steam with the gas mixture as it is delivered from any furnace to the kiln-chamber.

16. In a kiln, a plurality of kiln-chambers, a downdraft-furnace between each two adjacent kiln-chambers, each furnace having a discharge-opening leading to the bottom of the succeeding kiln-chamber, and an inlet-opening leading to the top of the preceding kiln-chamber, means to admit steam to the top of each furnace, and means to deliver steam to the outlet-port of each furnace.

17. In a kiln, a plurality of kiln-chambers, and a furnace for each kiln-chamber, each furnace having an upper charging-opening and a lower discharging - opening through which the fire may be drawn.

18. In a kiln, a plurality of kiln-chambers, and a downdraft-furnace for each kiln-chamber, each furnace having an opening in its top through which it may be charged and an opening in its bottom through which the fire may be drawn.

19. In a kiln, a plurality of kiln-chambers, each having an upper charging-opening and a lower discharge-opening, and a furnace for each kiln-chamber, each furnace having an upper charging-opening and a lower discharging-opening.

20. In a kiln, a plurality of kiln-chambers and a gas-producing furnace for each kiln-chamber, each furnace having an upper

130

- charging-opening and a lower discharging-opening, and removable grates within each gas-producing furnace and situated over the discharging-opening.
21. In a kiln, a plurality of connected kiln-chambers each having an upper opening through which material is delivered to said chamber, and a lower opening through which the burned material is discharged therefrom, and removable closures for said openings constructed when in place to prevent the passage of air through either opening while the kiln is in operation.
22. In a kiln, a plurality of kiln-chambers having communication with each other, and each having a charging-opening in its top and a discharge-opening in its bottom, and removable closures for said openings constructed when in place to prevent the passage of air through said openings while the kiln is in operation.
23. In a kiln, a plurality of kiln-chambers having communication with each other and each having a charging-opening in its top and a discharge-opening in its bottom, removable closures for said openings constructed to prevent the passage of air therethrough while the kiln is in operation, a trackway extending beneath all the chambers, an over-head trackway above the chambers, and a carrier on said latter trackway, whereby the action of gravity may be used to aid in the handling of the material burned in the kiln.
24. In a kiln, a plurality of kiln-chambers, a gas-producing furnace for each kiln-chamber, each furnace having an upper charging-opening and a lower discharging-opening, a cover for each discharge-opening, and a set of grate-bars within each furnace, one end of each set of grate-bars being supported by the cover for the corresponding discharge-opening, whereby when the cover is removed the grate-bars and fire may be removed through said opening.
25. In a kiln, a plurality of kiln-chambers, a gas-producing furnace for each kiln-chamber but separate therefrom, and means independent from the furnace whereby heated air may be delivered to that kiln-chamber in which the material is to be burned.
26. In a kiln, a plurality of kiln-chambers, a gas-producing furnace between each two adjacent kiln-chambers, each furnace being connected to the chambers on either side thereof, and means independent from the furnace to deliver heated air to that furnace in which the material is being burned.
27. In a kiln, a kiln-chamber having two inlets, one for gas and the other for air, said inlets being situated at widely-separated parts of the kiln, and means to deliver gas to one inlet and air to the other.
28. In a kiln, a kiln-chamber having an inlet for gas and a separate inlet for air, and means to deliver gas to the gas-inlet and air to the air-inlet, said inlets being separated from each other and situated at different parts of the kiln-chamber.
29. In a kiln, a plurality of kiln-chambers, a gas-generating furnace for each kiln-chamber, and an apparatus to force air into the furnace in which gas is being produced for the purpose of making gas therein, said apparatus being portable and capable of removal from one furnace to another.
30. In a kiln, a plurality of kiln-chambers, a gas-generating chamber for each kiln-chamber, a cover for the gas-generating-chamber in which gas is being generated, said cover having steam-generating means associated therewith.
31. In a kiln, a plurality of kiln-chambers, a gas-generating furnace for each kiln-chamber, a portable forced-draft apparatus to force air into the fuel in the furnace in which gas is being produced.
32. In a kiln, a plurality of kiln-chambers, a gas-producing furnace between each two adjacent kiln-chambers, each furnace being connected to the kiln-chambers on either side thereof, and a portable apparatus to force air into the fuel in that furnace in which gas is being produced whereby the gas is generated.
33. In a kiln, a plurality of kiln-chambers, a gas-generating furnace for each kiln-chamber, a portable steam-jet apparatus adapted to be associated with the furnace in which gas is being produced and force air into the fuel-bed therein for the production of gas.
34. In a kiln, a plurality of separate kiln-chambers, a gas-generating chamber between each two adjacent kiln-chambers and connected to each, means to establish a current of air through the chambers in succession, and means to divide the current of air into two currents having any desired relative volume prior to its entrance into the gas-generating chamber in which combustion begins, one of said currents passing through the said gas-generating chamber and the other being carried around the latter and reuniting with the first-named current at a point forward of the said gas-generating chamber, whereby combustion is only partially completed in said chamber and is completed at a point farther on.
35. In a continuous kiln, a series of separate kiln-chambers, a gas-generating chamber between each two adjacent kiln-chambers, means to establish a current of air through the chambers in succession, means to reduce to any degree the amount of air which passes through that gas-generating chamber in which gas is being generated, whereby the combustion in said chamber is only partially completed, and means to restore the maximum current of air to a chamber beyond.
36. In a continuous kiln, a series of connected kiln-chambers, a gas-generating chamber.

ber between each two adjacent kiln-chambers, means to establish a current of air through said chambers in succession, which current normally is sufficient to complete 5 combustion in any one of the gas-generating chambers, and means to shunt any desired portion of said air-current around the generating-chamber in which gas is being generated, and deliver said shunted portion of air 10 to a kiln-chamber beyond, whereby the amount of air which passes directly through the gas-generating chamber in which gas is being produced is insufficient to complete combustion therein.

15 37. In a continuous kiln, a plurality of kiln-chambers, a gas-generating chamber between each two adjacent kiln-chambers, means to regulate the quantity of air supplied to that generating-chamber in which 20 gas is being produced so that the gases which are being generated have a high heat value, means to supply to the gas at a point farther along an added quantity of air, and means to regulate this quantity of air so that the flame 25 is attenuated and combustion completed.

30 38. In a continuous kiln, a plurality of kiln-chambers, a gas-generating chamber situated between each two adjacent kiln-chambers and connected to each, means to establish a current of air through the kiln-chambers and gas-generating chambers in succession, means to shunt a portion of said current around the gas-generating chamber in which 35 gas is being produced and deliver said shunted portion to a kiln-chamber beyond, and dampers or valves to regulate the relative amounts of air shunted around and delivered to said gas-generating chamber.

40 39. In a kiln, a plurality of separate kiln-chambers, a gas-generating chamber between each two adjacent kiln-chambers and con-

nected to each, means to establish a current of air through the kiln-chambers and gas-generating chambers in succession, regulating devices by which the quantity of air supplied to that gas - generating chamber in which gas is being produced can be regulated so that the gas produced therein is of high heating value, and means to supply to the gas at a point farther on an added quantity 45 of air, whereby combustion is completed and the flame attenuated.

40. In a continuous kiln, a plurality of kiln - chambers, a downdraft - furnace between each two adjacent kiln-chambers and 50 connected to each, means to establish a current of air through the kiln-chambers and furnaces in succession, and means to shunt a portion of said current around the furnaces in which gas is being produced and deliver 55 said shunted portion back into the main current at a point farther on.

41. In a continuous kiln, a plurality of kiln - chambers, a downdraft - furnace, between each two adjacent kiln-chambers and 60 connected to each, means to establish a current of air through the chambers and furnaces in succession, a by-pass duct directly connecting successive kiln-chambers, and valves controlling said various by-pass ducts, where- 65 by a portion of the air may be shunted around the furnace in which the gas is being produced, and delivered to the succeeding kiln-chamber.

In testimony whereof I have signed my 70 name to this specification in the presence of two subscribing witnesses.

ARTHUR E. TRUESDELL.
